UNITED STATES PATENT OFFICE.

FREDRIK LJUNGSTRÖM, OF LIDINGO-BREVIK ORMBUNKEN, ERIK OTTO ERIKSSON, OF LIDINGO-BREVIK TALLHYDDAN, AND ISIDOR BROBERG, OF SKARSATRA, LIDINGON, SWEDEN, ASSIGNEES TO AKTIEBOLAGET LJUNGSTRÖMS ANGTURBIN, OF STOCKHOLM, SWEDEN, A CORPORATION.

CONDENSER PLANT FOR LOCOMOTIVES.

Application filed April 11, 1923, Serial No. 631,422, and in Sweden December 16, 1922.

Condenser plants for locomotives are known which comprise a liquid-receptacle serving as a heat accumulator and which is connected with an air-cooled part consisting of closed elements through the spaces of which air is forced by means of a fan or fans disposed between said elements and the receptacle. However, such arrangement of the different parts of the condenser plant necessitates a complicated structure, the fan or fans being not sufficiently accessible, whereas the space at disposal and limited by the loading gauge cannot be fully utilized.

The principal object of the present invention is to remove these drawbacks. To this end the invention consists in the fan or fans being arranged above both the air-cooled part and the liquid-receptacle.

Another object of the invention is to provide means to distribute the fluid to be cooled from said receptacle to the elements of said air-cooled part.

The accompanying drawing illustrates by way of example an embodiment of the invention. Fig. 1 shows a side view of a condenser plant constructed according to the invention. Fig. 2 is a cross-section through the same.

Referring now to Fig. 1 said figure shows a condenser plant belonging to a locomotive and placed on a separate car, which preferably may be coupled behind another car supporting the boiler, the driver's cab and the coal bunker of the locomotive. Supported on one end of the condenser car, preferably the end to be coupled to the boiler car in front thereof, is the driving machinery of the locomotive, for instance a steam turbine 10, which by means of the discharge pipe 11 is connected to the liquid-receptacle 12 of the condenser plant. From the turbine the movement is transmitted to the driving wheels 13 by means of a gearing 14 of any kind previously known, the movement from the last shaft of the gearing being transmitted to the driving wheels either by means of coupling rods or as shown in the figure, where the last shaft of the gearing itself forms the driving shaft or is joined to said shaft by means of an elastic or pivotable coupling. The exhaust steam of the turbine is led into the liquid-receptacle 12 and

directly condensed therein in the case of the liquid receptacle having the form of a water-cooled condenser of any known kind, for instance a jet condenser, the cooling water of which is forced through the air-cooled part 15 of the condenser by means of pumps in order to be recooled. In case of the air-cooled part being intended for condensing steam and the liquid-receptacle 12 being a steam storer operating under vacuum, the exhaust steam from the turbine is absorbed in known manner partly by the water of the liquid receptacle in order to be given off immediately or later on and then introduced through steam inlet pipes into the air-cooled part, in which it is condensed. In order to obtain a good cooling effect fans 16 are, according to the invention, arranged in the uppermost part of the condenser plant, said fans operating in known manner in a diaphragm or diaphragms disposed in the plane of the fans and separating the suction side of the fans from their pressure side. Said diaphragm or diaphragms consist preferably of a sheet metal plate or plates.

Fig. 2 shows a cross-section of said condenser plant. From this figure it is evident that the fans 16 are distributed above the air-cooled part consisting of two portions 15, 15 as well as above the liquid-receptacle 12 in such a way that the cooling air passes in the direction of the arrows 17 first through the air-cooled part and then through the fans. Thus, the fans have two air inlets, viz, one inlet through each of the portions 15, 15 of the air-cooled part, but only one outlet, directed straight upwards. The fans 16 are mounted on pillars 18, standing right up from the condenser receptacle 12, and are driven in known manner by a longitudinally extending common shaft 19 by means of gearings not shown in the drawings. The two portions 15, 15 of the air-cooled part extend from pipes 20, situated close to the lateral contours of the loading gauge, downwards to the receptacle 12 to which the elements of the air-cooled part are directly fixed by means of devices of any known kind.

By means of the arrangement of parts according to the present invention in which the fans of the condenser plant are placed above the condenser receptacle as well as

above the air-cooled part the advantage is gained, in comparison with previous constructions, that the air intake of the fans is placed relatively high above the ground so that dust etc. is not sucked in to any great extent. By letting the fans suck the cooling air through the air-cooled part instead of forcing the air through the said part as was previously done the advantage is also gained that dust or the like, which may be carried along by the air, first passes the air-cooled part and is deposited on the elements, chiefly on their outer side where the elements are most easily reached for cleaning purposes. The air entering the fans later on has in this way to a great extent been freed from dust and larger bodies such as leaves or the like, whereby the fans will operate in the purest possible air, thus preventing them and their driving means from being choked with foreign matter. By sucking the air through the air-cooled part a novel technical improvement is also attained, consisting of a more even air current, distributed more uniformly over the whole surface of the air-cooled part. The air sucked through the cooling elements by the fans is immediately ejected into the air above the condenser plant where it is almost instantaneously blown away, and therefore there is no danger of the air being again sucked through the air-cooled part after having once passed through the condenser and having been heated there. In comparison with previous constructions the power necessary for driving the fans may also be decreased by the flow of air passing directly into the atmosphere without passing through any channel and by the inlet channels of the fan being made large, whereby the resistance to the air current is considerably lessened. The elements of the air-cooled part are, moreover, so arranged in relation to the other parts of the condenser plant, that the driver has a good view of the line especially when the locomotive is backing, this being particularly important during shunting, when the driver must devote his attention directly to the rails and to the positions of the points. By the present invention the advantage is also gained, that all the parts of the condenser plant which need to be looked after may be arranged on the outer side, which has not been the case in

previous constructions, where for instance the fans have been situated within the condenser plant and entirely surrounded by said plant, while the fans according to the present invention are easily accessible for inspection, mounting and dismounting purposes. In the same way the portions of the air-cooled part are easily accessible for inspection since they are at the sides of the car, where they may be inspected and cleared of impurities by a person on the ground. The elements of the air-cooled part, which must be considered the most easily damaged parts of the condenser plant, have also been given a protected position, as they are not subjected to damages arising from heavier bodies or the like falling down from viaducts or workshops nor to the risk of being begrimed by the combustion gases from the locomotive as is the case if the elements are arranged in the ceiling of the condenser car.

Several modifications of the invention may well be imagined without deviating from its principle thereof. Thus the invention is independent of whether the condenser plant is placed on the same car as the boiler of the locomotive or if its two aggregates are placed on separate cars. The invention is further independent of the shape and the position of the driving aggregate of the locomotive.

What we claim as new and desire to secure by Letters Patent of the United States of America is:—

A condenser plant for locomotives and similar vehicles comprising a receptacle extending in the longitudinal direction of the locomotive, means to introduce the fluid to be cooled into said receptacle, an air-cooled part arranged on the side of said receptacle and consisting of a number of closed elements placed transversely of the locomotive, means connecting said receptacle with the air-cooled part and adapted to distribute the fluid to be cooled to the elements of the air-cooled part, and a fan placed above both the air-cooled part and the liquid receptacle, said fan being adapted to suck air between said elements.

In testimony whereof we affix our signatures.
